HIGH-TENSION MAGNETO

Oscar L. Bachman, Springfield, Mass., assignor
to American Bosch Corporation, Springfield,
Mass., a corporation of New York

Application May 10, 1944, Serial No. 535,005

10 Claims. (Cl. 171—209)

1

The present invention relates to high tension magnetos of timer drive types for single or multi-cylinder internal-combustion engines operating on any suitable cycle, and particularly to such magnetos incorporating a unitary subassembly of certain electrical and other parts removable from and replaceable in the housing or outer stator magnetic structure as a unit. The invention also relates to such unitary subassemblies as new articles of manufacture for spare and replacement parts in magnetos of such types, wherein the magneto shaft is driven at the cam shaft speed of the associated engine and drives without speed change the magnetic rotor and the circuit breaker rotor or cam of the magneto, and also the distributor rotor where the magneto is of the multi-cylinder type.

Heretofore, it was usual in some magnetos of timer drive types to support their high tension ignition coils from the housings, or in such other wise that the removal of the coil from the assembled magneto required the prior removal of at least some of the stator parts of the circuit breaker mechanism (as for instance the contact elements with or without their supporting member or disc) and certain electrical connections thereto, in addition to the magnetic rotor, and also the cap or plate and rotor of the distributor mechanism where provided for multicylinder magnetos. In others of such types, the coil was removable through the bottom of the magneto, after the magneto was removed from the engine and after its drive or impulse coupling was disassembled from the magnetic rotor or removed with it. Both of these types of construction resulted in considerable service time in the case of inspection, adjustment, repair or replacement of the coil, or other electrical part other than the distributor mechanism, and sometimes resulted also in changes in the timing of the magneto on the engine, or in the setting of the breaker mechanism, or in the edge distance of the magneto, which changes were harmful to the continued life and performance of the magneto and engine.

In accordance with my invention, the unitary subassembly including the high tension ignition coil, the stator parts of the breaker assembly, and certain stator magnetic parts supporting them, as well as the primary and secondary conductors connecting the coil windings with other electrical parts, form a unitary structure which may be removed as a unit from the housing, preferably through the top of the housing so as not to require the disengagement of the magneto from the engine. The unit may then be inspected, re-

paired or replaced in whole or in part before it is replaced in the magneto. Thus the time for service is reduced, consequent mistiming, misalignment and misadjustment are rendered less likely, and if desired the entire electrical system, except the distributor mechanism in the case of a multicylinder engine, may be replaced at low cost and without the usual long interruption in service upon development of wear, electrical breakdown or other operational fault in any of those electrical and other parts. Since those electrical parts include, as a practical matter, all the weaker elements of the magneto most liable to operative change and breakdown requiring inspection, adjustment, repair and replacement, this construction provides important advantages in the field of use and particularly in those services distant from repair stations.

Accordingly, the primary object of my invention is to provide in magnetos of timer drive types, unitary subassemblies of certain electrical and other normally stationary parts which are removable from and replaceable in the magneto as a unit, preferably without removing the magneto from the engine.

Another object is to provide a unitary subassembly in magnetos of this kind in which the stator elements of the breaker assembly, and the high tension ignition coil with conductors electrically connected to primary and secondary windings thereof, are supported by the inner stator magnetic structure so as to be removable from and replaceable as a unit in the outer stator magnetic structure. Preferably this unitary subassembly has a bearing for the drive shaft of the magneto to reliably support it near its upper end at a place longitudinally separated as far as practical from a bearing in the lower end of the outer stator magnetic member. Preferably also, this inner stator magnetic structure is detachably fastened to the outer stator magnetic structure so as to be removable therefrom and at the same time to stabilize the drive shaft in its rotation in the assembled magneto, and the high tension conductor connected to the secondary winding of the coil is fastened to the member supporting the stator elements of the circuit breaker to reliably secure the conductor in place. This unitary subassembly is especially adapted to a magneto of this kind in which the inner stator magnetic structure has a hollow longitudinal portion through which the drive shaft extends and around which the coil is located, and also has at least one upper and one lower wing extending radially from the longitudinal portion at op-

2

posite faces of the coil. Also it is well adapted to such magnetos in which the outer stator magnetic structure or housing has an open top through which the unitary structure may be removed and replaced while the magneto is mechanically connected to the engine, and a bearing near its lower end, particularly in the case of multicylinder types of magnetos in which the distributor cap is detachably fastened over the open end of the housing and has a main electrode in electrical connection with the distributor rotor and with the high tension conductor leading to the secondary winding of the ignition coil of the unitary subassembly.

Another object is to provide unitary subassemblies of this kind as new articles of manufacture for use as spare or replacement parts in magnetos of this kind.

Other objects and advantages will appear from the following disclosure of my invention as applied, for example, to several embodiments of four-cylinder magnetos of the timer drive type, taken in conjunction with the accompanying drawings, in which

Fig. 1 is a central vertical section, partly broken away, of one form of magneto within the invention in which the magnet and laminated steel pole shoes therefor are cast in a housing of non-magnetic material and in which a laminated sleeve is adapted to rotate between the outer and inner stator magnetic structures; Fig. 2 is a plan view of the magneto of Fig. 1 with the distributor cap and rotor removed to show particularly the circuit breaker mechanism; Fig. 3 is an exploded view, principally in central vertical section, of the magneto, showing, among other things, the unitary subassembly by itself removed from the outer stator magnetic structure; and Fig. 4 is a similar exploded view of another embodiment of a magneto within the invention in which the magnet is fastened to the drive shaft and rotatable with it between the inner and outer stator magnetic structures.

Referring first to the embodiment of Figs. 1-3, the magneto has an outer stator magnetic structure or housing 1 comprising an aluminum-zinc cylindrically shaped member 2 in which there is cast-in the permanent magnet 3 with laminated pole shoes therefor, and a vertical stack of laminations 4 having a pole shoe. The contracted bottom portion 5 of the housing carries a bearing 6 and, if desired, is suitably fastened to a housing and engine flange member 7 for housing an impulse coupling or ignition timing governor or both, and for fastening the magneto on the multi-cylinder engine with which it is to be associated.

The magneto also has an inner stator magnetic structure 8 which forms a unitary subassembly detachably fastened by screws 9 to the housing 1 in timed position therein at 9'. It comprises a longitudinally extending hollow stack of sheet steel laminations 10 with a radially extending wing 11 at its top and a radially extending wing 12 at its bottom, the bottom wing being held in place by the snap ring 13. Between the upper and lower wings is a high tension ignition coil 14 comprising primary winding 15 and secondary winding 16. This coil is located around the portion 10 of the inner stator magnetic structure with the wings 11 and 12 at the respective upper and lower surfaces of the coil. The upper wing is cast as an insert in the non-magnetic metal member 17 which forms a supporting member for the circuit breaker stator elements and which serves to locate the inner stator magnetic structure 8

within the housing 1. These circuit breaker stator elements include, as usual, the circuit breaker contacts 18 carried respectively by the pivoted lever 19 and the adjustably stationary support 20. They also include the condenser 21 which is electrically connected by the conductor 22 to the circuit breaker terminal 23 which also is electrically connected by the low tension conductor 24 to the live terminal of the primary winding 15 of the ignition coil. The inner stator magnetic structure 8 is provided near its upper end with a plain bearing 25.

The drive shaft 26 projects below the magneto, so as to be driven by the internal combustion engine (not shown) at the cam shaft speed thereof. This shaft is reliably supported near its upper and lower ends in the bearings 6 and 25. The circuit breaker cam 27 is detachably fastened on the shaft 26 near the upper end thereof by means of a key and the screw 28 and a washer 29 in operative cooperation with the follower block of the lever 19. To this shaft 26 is also fastened the magnetic rotor 30 comprising laminated sheet steel sleeve portions 31 and 32, rotatable as a unit by the shaft in magnetic inductive relation with the lower wing 12 and the pole shoes of the outer stator magnetic structure.

The outer and inner magnetic structures 1 and 8 of the magneto are so arranged that in one position the sleeve portions 31 and 32 connect the north pole of the magnet 3 to the lower wing 12 of the longitudinal portion 10, and then, upon 90° rotation, connect that magnet pole to the upper wing 12 through the stack 4, thus reversing the direction of flux through the longitudinal portion 10 and the coil 14 at 90° intervals. In the position shown in Fig. 1, the flux passes from the north pole of magnet 3 to the sleeve portion 31 and thence into and through the lower wing 12, from which it passes into and upwardly through the longitudinal portion 10 and through the upper wing 11 into the stack 4. From this the pole shoe of the stack passes the flux into the other portion 32 of the sleeve and back to the other pole of magnet 3. At substantially each period of the reversal of the flux in this way, the interrupter contacts 18 are opened by the cam 27 to generate an ignition impulse in the secondary winding 16 in the well known way.

The distributor mechanism of the magneto includes the distributor rotor 33 detachably fastened by friction on the end of the cam 27. It also includes a distributor cap 34 which has sparkplug electrodes 35 electrically connected by wires 36 to the sparkplugs in the cylinders of the engine and sequentially cooperative with the electrode 33 of the distributor rotor. The cap also contains a centrally located main electrode 37 in electrical connection with the electrode 33 of the distributor rotor, and a conductor insert 38 extending into connection with the insulated high tension conductor 39 connected to the terminal of the secondary winding 16 of the ignition coil, so as to conduct the current impulses periodically generated in the secondary winding to the electrode of the distributor rotor for distribution thereby. This high tension conductor 39 is detachably fastened in a notch of the supporting member 17 by a strap 40, so as to remain reliably fastened in position as a part of the unitary subassembly.

In order to remove the unitary subassembly 8 from the magneto, the distributor cap 34 is first detached by removing the screws at 41, and then the distributor rotor is pulled off the cam exten-

sion. The screw 28 is then removed to release the cam from the shaft and likewise the screws 9 holding the inner stator magnetic structure within the housing. Thereafter the unitary subassembly may be removed as a unit through the open top of the outer stator magnetic structure 1, for inspection, adjustment, repair or replacement of any of the electrical parts including the coil 14, contact points 18, condenser 21, and the connections of the high and low tension conductors 39, 24 and 22. This inner stator magnetic structure 8, or a new spare or replacement one, may be replaced in the outer stator magnetic structure 1, and likewise the cam and distributor mechanism. Since the removal and replacement is through the top and the shaft 26 is driven on its lower projecting end, the magneto need not be removed from the engine for this operation. Also since this replacement with a spare unit is so simple and rapid, without the need for special tools, it may be performed in the field by the ordinary engine user.

Now referring to the second embodiment as shown in Fig. 4, the outer stator magnetic structure 42 comprises the non-magnetic housing portion 43 in which are cast the two stacks of suitably arranged laminations 44 having pole shoes. This structure has an open top, and a contracted bottom portion 45 which carries a plain bearing 46 for the drive shaft 47, and is attached to a housing and engine mounting flange 48, as in the previous embodiment. The unitary subassembly 49 of this embodiment includes, somewhat as before, a hollow longitudinal laminated portion 50 with laminated upper wings 51 and lower wings 52, extending radially at the upper and lower faces of the high tension ignition coil 53. The subassembly is held together by the snap ring 54. This subassembly has a breaker plate 55 for the circuit breaker stator elements 56, said plate being fastened to the laminated structure 50, 51 and having an upper bearing 57 for the drive shaft 47 and an opening for the passage therethrough of the insulated high tension coil conductor 59. A rubber grommet 60 holds this conductor reliably in place in the breaker plate. The ignition coil 53 containing primary and secondary windings as before, is located around the longitudinal magnetic portion 50 with its upper and lower surfaces between the upper and lower 50 wings 51, 52 of the inner stator magnetic structure.

The drive shaft 47 projects below the magneto and is adapted to be driven as before by an internal combustion engine at the cam shaft speed thereof. It is reliably supported in the upper and lower bearings 46 and 57 and is fastened to the plate 61 carrying the permanent magnet or magnets 62. On the upper end of the shaft is keyed the circuit breaker cam 63 detachably fastened to the shaft by the screw 64 and washer 65. On the upper end of the cam is frictionally held the rotor 66 of the distributor mechanism, and, as before, the distributor cap 67 is fastened in position over the open end of the housing. When the magneto is assembled, the high tension coil conductor 59 contacts the conductor insert 68 in the distributor cap 67 which extends to the main electrode 69 in contact with the electrode of the distributor rotor 66 for sequential distribution of the ignition impulses generated in the coil 53 to the sparkplug electrodes 70 and wires 71.

It will be apparent from the preceding that after removing the distributor cap 67 and rotor 66, and the circuit breaker cam 63, the unitary

subassembly 57 may be removed as a unit from the magneto for inspection, adjustment, repair and replacement of the electrical parts comprising the ignition coil 53, circuit breaker contacts 56, condenser and the high and low tension conductors electrically connected to the coil and to the main electrode 68 of the distributor cap and the terminal of the circuit breaker.

From the foregoing as to both embodiments, it will be apparent that the unitary subassembly, including the high tension ignition coil, the stator parts of the breaker mechanism and certain stator magnetic parts supporting them, as well as the primary and secondary conductors connecting the coil windings with other electrical parts, form a unitary structure which may be removed from the housing as a unit and which may be inspected, adjusted, repaired, and/or replaced in whole or in part before reassembly in the magneto. These electrical parts constitute the weaker elements of the magneto and those most likely to require adjustment and replacement, particularly the ignition coil, the contact points and the condenser. Thus, as a result of this unitary subassembly, removable from and replaceable in the magneto as a unit, service may be performed in the field of use by an ordinary engine user and without special tools, and without removing the magneto from the engine. In this way, and particularly if the entire subassembly is replaced, an engine, which became inoperative from ignition trouble, may be rendered operative in the minimum time and at low cost.

It is apparent that many modifications may be made in the magnetos herein specifically disclosed without departing from my invention. For instance, the magneto may provide for single cylinder ignition without using any distributor mechanism in which case the high tension coil conductor would be connected directly to the sparkplug of the engine. Or the magneto may provide for ignition of multicylinder engines of other than four cylinders. Furthermore, the magnetic circuit of the magneto may be of any of the well known or other types, whether the magnet or magnets rotate or are stationary, so long as the central longitudinal stack forms a part of the stator magnetic circuit surrounded by the ignition coil to form the core thereof and have the flux therein either reversed or reduced therethrough at the periods of ignition. Also the circuit breaker and distributor mechanism may be of any suitable types so long as the circuit breaker cam and distributor electrode are rotatable with the drive shaft of the magneto. Also the ignition coil may have any suitable construction. These and other changes are intended to be covered by the broad terms of the appended claims.

Having thus described my invention, what I claim is:

1. In a high tension magneto of the timer drive type having an outer stator magnetic structure, a drive shaft, a magnetic rotor fastened to the shaft, and a circuit breaker cam fastened to the shaft; and a unitary subassembly which is removable from the drive shaft, the outer stator magnetic structure and magnetic housing and replaceable on said drive shaft, in said outer stator magnetic structure and in said magneto housing as a unit and which comprises an inner stator magnetic structure, a high tension ignition coil which is supported by the inner stator magnetic structure and which has primary and secondary windings, circuit breaker stator elements sup-

ported by the inner stator magnetic structure, a high tension conductor electrically connected to the secondary winding, and a low tension conductor electrically connected to the primary winding and to the stator elements of the circuit breaker.

2. A magneto in accordance with claim 1, in which the inner stator magnetic structure of the unitary subassembly has a bearing for the drive shaft.

3. A magneto in accordance with claim 1, in which the inner stator magnetic structure of the unitary subassembly is detachably fastened to the outer stator magnetic structure.

4. A magneto in accordance with claim 1, in which the high tension conductor connected to the secondary winding of the coil of the unitary subassembly is fastened to the member supporting the stator elements of the circuit breaker.

5. A magneto in accordance with claim 1, in which the inner stator magnetic structure of the unitary subassembly has a hollow longitudinal portion through which the drive shaft extends and around which the coil is located, at least one upper magnetic wing, and at least one lower magnetic wing, said wings extending radially from the longitudinal portion at the respective upper and lower faces of the coil.

6. In a high tension magneto of the timer type having an outer stator magnetic structure with an open top and with a bearing near its lower end, a drive shaft journaled in the bearing and projecting below the outer stator magnetic structure, a magnetic rotor fastened to the shaft, a circuit breaker cam fastened to the shaft near the upper end, and a cap detachably fastened to the outer stator magnetic structure over the open top thereof; and a unitary subassembly which is detachably fastened to the outer stator magnetic structure and is removable therefrom and replaceable therein as a unit through the open top of the outer stator magnetic structure while the magneto is in operative position on an engine and which comprises an inner stator magnetic structure having an upper bearing for the shaft, a high tension ignition coil which has primary and secondary windings and which is supported by the inner stator magnetic structure, circuit breaker stator elements supported by the inner stator magnetic structure, a high tension conductor electrically connected to the secondary winding, and a low tension conductor electrically connected to the primary winding and to the stator elements of the circuit breaker.

7. In a high tension multicylinder magneto of the timer drive type having an outer stator magnetic structure, a drive shaft, a magnetic rotor fastened to the shaft, a circuit breaker cam fastened to the shaft, and distributor mechanism which includes a distributor rotor fastened to the shaft and which also includes stationary spark plug electrodes supported by the outer stator magnetic structure in sequential cooperation with the distributor rotor; and a unitary subassembly which is removable from and replaceable in the outer stator magnetic structure as a unit while the magneto is in operative position on an engine and which comprises an inner stator magnetic structure, a high tension ignition coil which has primary and secondary windings and which is supported by the inner stator magnetic structure, circuit breaker stator elements

supported by the inner stator magnetic structure, a high tension conductor electrically connected to the secondary winding and to the distributor rotor, and a low tension conductor electrically connected to the primary winding and to the stator elements of the circuit breaker.

8. In a high tension multicylinder magneto of the timer drive type having an outer stator magnetic structure which is open at the top and which has a bearing near its bottom, a drive shaft projecting longitudinally outwardly of the bearing, a magnetic rotor fastened to the shaft, a circuit breaker cam detachably fastened to the shaft near the top thereof, and distributor mechanism which includes a distributor rotor detachably fastened to the shaft and also which includes a distributor cap detachably fastened over the open top of the outer stator magnetic structure with its sparkplug electrodes in sequential cooperation with the distributor rotor and with its main electrode in electrical connection with the distributor rotor; and a unitary subassembly which is removable from and replaceable in the outer stator magnetic structure as a unit through the top thereof while the magneto is in operative position on an engine and which comprises an inner stator magnetic structure having an upper bearing for the shaft, a high tension ignition coil which is supported by the inner stator magnetic structure and which has primary and secondary windings, circuit breaker stator elements fastened to the inner stator magnetic structure, a high tension conductor electrically connected to the secondary winding and to the main electrode of the distributor cap, and a low tension conductor electrically connected to the primary winding and to the stator elements of the circuit breaker.

9. As a new article of manufacture, a unitary subassembly for a high tension magneto of the timer drive type and removable from the magneto housing as a unit through the top thereof while the magneto housing and drive are in operative position on an engine, said subassembly comprising a stator magnetic structure, a high tension ignition coil which is supported by the stator magnetic structure and which has primary and secondary windings, circuit breaker stator elements supported by the stator magnetic structure, a high tension conductor electrically connected to the secondary winding, and a low tension conductor electrically connected to the primary winding and to the stator elements of the circuit breaker, said elements of said subassembly being secured together and said magneto having a removable cap whereby said subassembly may be removed from the magneto housing or replaced therein as a unit.

10. A new article of manufacture in accordance with claim 9, in which the high tension conductor of the unitary subassembly is fastened to the member supporting the stator elements of the circuit breaker.
